SOUND RECORDING APPARATUS

Otto Zecha, Vienna, Austria

Application October 25, 1935, Serial No. 46,758.
In Austria February 14, 1935

4 Claims. (Cl. 274—13)

This invention relates to improvements in arrangements for cutting sound records by the employment of an ordinary talking machine of the kind in which the rotary movement of the centre pin of the turntable of the talking machine rotates a screw threaded guide spindle which is supported in a bearing at one end only and is prevented from participating in the rotary movement of the centre pin of the turntable by a nut 5 riding on said screw-threaded guide spindle and connected by a pivoted connection with the supporting arm of the sound box carrying the cutting needle.

The essential feature of the present invention 15 consists in that the pivoted connection is attached to the supporting arm of the sound box by means of an intermediate member which is adjustably secured to said pivoted connection and is provided with means for its removable attachment to said supporting arm, in order to permit the application of the arrangement to differently shaped sound box supporting arms.

In view of the provision of the adjustable intermediate member it is possible to use the arrangement for cutting sound records in connection with sound box arms of different shapes, e. g. bent sound box arms or straight sound box arms. In view of this construction it is possible to place the intermediate member at different angles with 30 respect to the said pivoted connection, in order to safeguard the same distance between the sound box and the nut riding on the screw-threaded guide spindle no matter of the shape of the sound box arm. Thus the arrangement for cutting 35 sound records can be used in connection with any type of talking machines and sound box arms.

A form of construction embodying the invention is shown by way of example in the accompanying drawing, in which:

40 Fig. 1 is a perspective view of recording apparatus according to the present invention.

Fig. 2 shows a detail of the same.

Figs. 3 and 4 are side elevations showing how the record disk is mounted on the turn-plate.

45 Referring to Fig. 1, the sound recording apparatus according to the invention consists essentially of a two-part articulated guide rod 9 adapted for coupling by one end to a distancing piece 8 to which there is riveted an adjustable strap 7 for attachment to the sound-box arm 5 of the gramophone. To the other end of the guide rod 9 there is secured a half-nut 10 which rides on the conveyor spindle 11, the screw threading on the inside of the half-nut being in 50 engagement with the threading on the outside of

the conveyor spindle. Spring means associated with the nut 10 or the inherent resiliency of the walls of this nut serve to retain these two parts, nut and spindle, firmly in engagement with each other. The one end of the spindle 11 is supported 5 in a casing 12 adapted to be fitted, by means of a slotted sleeve 13, over the centre pin integrally formed on the end of the main driving shaft of the gramophone. A helical spring 14 fitted over the sleeve 13 presses this sleeve into gripping contact with the main driving shaft of the gramophone, and causes the rotary movement of this shaft to be transmitted from this sleeve, through the intermediary of bevel or worm gearing housed in the casing 12, to the conveyor spindle 11. 15

The record disk 3 does not lie directly upon the turn-plate 1 but upon an interposed facing disc 2 (see Fig. 3). This disc 2 is provided with a rough under surface 2' with which it bears against the turn-plate 1, and on its upper side with prominences or studs 4 adapted to engage in suitable apertures in the record disk 3, so that the record disc and the facing disk constitute as it were a unit. The frictional resistance between the rough under surface 2' of the facing disk 2 and the turn-plate 1 is so great that it is certain to exceed that resulting from the pressure of the groove cutting needle. If desired the engaging studs or the like can be dispensed with, in which case the upper surface of the facing disk is also roughened or provided with a rough coating. This rough coating can be made to cover the entire surface of the facing disk, or may consist of single segments or otherwise shaped pieces or strips which may be radially or tangentially disposed or in the form of annuli. The conditions could of course also be reversed, the record disk being provided on its under side with a rough coating or engaging studs and thus anchored to the suitably constructed turn-plate or facing disk. 20 If desired, the anchoring could also be effected by means of an annular or disc shaped attachment adapted to grip the record disk at its outer edge or at its centre by means of studs or the like and to engage in suitable holes or recesses in the facing disk or turn-plate. 25

In the form of construction shown in Fig. 1 the facing disk 2 is provided with studs 4 adapted to engage in holes in the recording disk. The end 15 of the helical spring 14 is formed into a loop or ring adapted to fit over one of the studs 4, thus still further increasing the security of the hold between the recording disk 3 and the facing disk 2. 30

Before recording is commenced, the record disk 35

3 is placed upon the facing disk 2, and this then placed in position on the turn-plate 1. The conveyor-spindle unit is then fitted by means of the sleeve 13 to the projecting end of the main driving shaft of the gramophone which is firmly gripped by the action of the helical spring 14. On the other hand, the distancing piece 8 is attached to the sound-box arm 5 by means of the strap 7. The distancing piece and the conveyor spindle unit are then coupled together by means of the guide rod 9, by screwing the one end of the latter to the distancing piece 8 and placing the nut 10 in position on the spindle 11.

The provision of the distancing piece 8 ensures the applicability of the device irrespective of the shape and curvature of the sound-box arm. Thus, Fig. 1 shows a bent arm with an acoustic sound-box, and Fig. 2 a straight arm with an electric sound-box.

20 Further, the articulate guide rod 9 likewise permits of the universal application of the device according to the invention, irrespective of the height of the sound-box, since it permits of keeping the flying spindle 11 always in a horizontal position.

With disc records there is the danger of warping and buckling. This drawback is overcome, in accordance with the invention, by pressing the thin record disc upon its base, either at the outer 30 edge or at the centre, by means of a ring or disk 16 of metal.

A form of construction embodying this feature is shown in Fig. 4.

If the record disc itself be provided on the 35 under side with a rough coating or with studs or the like engaging elements, it becomes unnecessary to provide a separate facing disk, and the turn-plate can be furnished with the necessary counter engaging elements.

40 One of the conditions that must be fulfilled if a satisfactory record is to be obtained is that the cutting taken by the style needle be of the same thickness throughout, that is to say that the sound groove cut should be of exactly the same 45 depth throughout. In order to make it easier for the novice to observe this requirement, and to provide a visible check on its fulfilment, the invention further provides for the use of record discs made up of layers of different colors. To a 50 foundation disk for example of red color there are applied one or more delimited or merging, differently colored layers. Assuming the proper thickness of the cutting to be for example just down to the red color, the bottom of the groove 55 should always be of this color. If the bottom of the groove appears pink or if red parts appear in the cutting it will be seen at once that the groove is too shallow or too deep, respectively. The load on the cutting needle must then be altered or the 60 turn-plate set to run accurately in one plane. In any case the user is at once warned that the conditions are not right for obtaining satisfactory recording. Since, as is well known, the cutting runs inwards it is easy to keep the same under 65 observation, the more so since when engaging

studs are employed which project above the surface of the record disk the cutting becomes wound around these studs as on a reel.

I claim:

1. An arrangement for cutting sound records by the employment of an ordinary talking machine with turntable, comprising in combination a bearing, means on said bearing for securing it to the centre pin of the turntable of the talking machine, a screw-threaded guide spindle supported in said bearing with one of its ends only, a nut riding on said guide spindle, connecting means pivoted to said nut, an intermediate member adjustably secured to said connecting means, and means on said intermediate member for its removable attachment to the supporting arm of the sound box of a talking machine. 5

2. An arrangement for cutting sound records by the employment of an ordinary talking machine with turntable comprising in combination a bearing, means on said bearing for securing it to the centre pin of the turntable of the talking machine, a screw-threaded guide spindle supported in said bearing with one of its ends only, a nut riding on said guide spindle, articulated connect- 20 ing means pivoted to said nut, an intermediate member adjustably secured to said connecting means, and means on said intermediate member for its removable attachment to the supporting arm of the sound box of a talking machine. 25

3. An arrangement for cutting sound records by the employment of an ordinary talking machine with turntable comprising in combination a slotted sleeve adapted to be placed on the centre pin of the turntable of the talking machine, a helical spring wound round said sleeve for pressing the sleeve into gripping engagement with said centre pin, a screw-threaded guide spindle supported in said bearing with one of its ends only, a nut riding on said guide spindle, connecting means pivoted to said nut, an intermediate member adjustably secured to said connecting means, and means on said intermediate member for its removable attachment to the supporting arm of the sound box of a talking machine. 30

4. An arrangement for cutting sound records by the employment of an ordinary talking machine with turntable, comprising in combination a slotted sleeve adapted to be placed on the centre 35 pin of the turntable, a stud projecting from said turntable, a helical spring wound round said sleeve for pressing the sleeve into gripping engagement with said centre pin, one end of said spring being secured to said sleeve and the other end of the spring being attached to said stud, a screw-threaded guide spindle supported in said bearing with one of its ends only, a nut riding on said guide spindle, connecting means pivoted to said nut, an intermediate member adjustably secured to said connecting means, and means on said intermediate member for its removable attachment to the supporting arm of the sound box of a talking machine. 40

5. An arrangement for cutting sound records by the employment of an ordinary talking machine with turntable, comprising in combination a slotted sleeve adapted to be placed on the centre 45 pin of the turntable, a stud projecting from said turntable, a helical spring wound round said sleeve for pressing the sleeve into gripping engagement with said centre pin, one end of said spring being secured to said sleeve and the other end of the spring being attached to said stud, a screw-threaded guide spindle supported in said bearing with one of its ends only, a nut riding on said guide spindle, connecting means pivoted to said nut, an intermediate member adjustably secured to said connecting means, and means on said intermediate member for its removable attachment to the supporting arm of the sound box of a talking machine. 50

6. An arrangement for cutting sound records by the employment of an ordinary talking machine with turntable, comprising in combination a slotted sleeve adapted to be placed on the centre 55 pin of the turntable, a stud projecting from said turntable, a helical spring wound round said sleeve for pressing the sleeve into gripping engagement with said centre pin, one end of said spring being secured to said sleeve and the other end of the spring being attached to said stud, a screw-threaded guide spindle supported in said bearing with one of its ends only, a nut riding on said guide spindle, connecting means pivoted to said nut, an intermediate member adjustably secured to said connecting means, and means on said intermediate member for its removable attachment to the supporting arm of the sound box of a talking machine. 60
